(57) **CLAIM**

The ornamental design for a low volume beverage dispenser, as shown.

DESCRIPTION

FIG. 1 is a perspective view of a low volume beverage dispenser showing our design.

FIG. 2 is a left-side elevational view;

FIG. 3 is a front elevational view;

FIG. 4 is a right-side elevational view, showing the side opposite that in FIG. 2;

FIG. 5 is a rear elevational view, showing the side opposite that in FIG. 3;

FIG. 6 is a top plan view;

FIG. 7 is a bottom plan view; and,

FIG. 8 is a rear elevational view of an alternative embodiment of the low volume beverage dispenser, the other views being the same as as FIGS. 1-4 and 6-7.

1 Claim, 5 Drawing SheetsFIG. 1

FIG. 2

FIG. 3

FIG. 5

FIG. 4

FIG. 6

FIG. 7

FIG. 8

UNITED STATES PATENT AND TRADEMARK OFFICE
CERTIFICATE OF CORRECTION

PATENT NO. : Des. 462,225 S
DATED : September 3, 2002
INVENTOR(S) : Melvin D. Kyees et al.
